BABY WALKER

Joseph D. Carpenter, Los Angeles, and Fred E. Golding,
South Pasadena, Calif., assignors to Aeon Industries, Inc., doing business as Pride Products Company, Glendale, Calif., a corporation of California

Filed Feb. 23, 1968, Ser. No. 10,703

Term of patent 14 years

U.S. Cl. D15—1
Int. Cl. D12—12

FIG. 1 is a front perspective view of a baby walker showing our new design;

FIG. 2 is a rear perspective view of the baby walker of FIG. 1;

FIG. 3 is a top plan view of the baby walker of FIG. 1; and

FIG. 4 is a front elevation view of the baby walker of FIG. 1.

We claim:

The ornamental design for a baby walker, as shown and described.
